CONVEYER CHAIN

Warren A. Dickinson, Philadelphia, Pa., assignor
to Proctor & Schwartz, Incorporated, Phila-
delphia, Pa., a corporation of Pennsylvania

Application May 4, 1934, Serial No. 723,993

13 Claims. (Cl. 198—189)

This invention relates to pole-carrying chains for conveyers such as those used in drying, processing, and other apparatus for handling yarns in skein form, tobacco leaf in bunch form, or other materials capable of being supported on and suspended from poles for transportation through the apparatus, wherein the poles are disposed in laterally spaced substantially parallel relation to each other transversely of the conveyer with the opposite ends of the poles respectively resting on a pair of laterally spaced carrying chains constituting the conveyer.

Different kinds of material undergoing different processings or special handlings require different spacings of the poles on the carrying chains. Prior to the present invention, it has been necessary to provide completely different chains for each of the different pole spacings required, each link of each chain being provided with one or more individual pole sockets, which, in order to space the poles uniformly on the chains, require the provision of chains of different pitches. This in turn requires the provision of differently pitched sprockets to accommodate the differently pitched chains.

The object of the present invention is to provide a single standard form of fixed pitch chain adapted to receive interchangeable series of different socket attachments wherein the spacing of the pole sockets in each series of attachments is different from those of the other series, thereby obviating the necessity for providing completely different chains under the circumstances noted.

More specifically the invention concerns the provision of a fixed pitch chain wherein each link thereof is provided with a relatively flat surface so arranged thereon as to effect longitudinal alignment of the flat surfaces of the links throughout the pole-carrying run of the chain; and the provision of plural series of readily detachable and interchangeable pole socket attachments adapted to be secured to the aligned flat surfaces of the links respectively.

Another object of the invention is to so construct the attachments that a series thereof for any given spacing may be quickly produced, thereby obviating the necessity for the manufacturer to carry in stock great numbers of different pole-carrying attachments.

The construction of the chain and of the attachments therefor will be disclosed hereinafter, reference being had to the accompanying drawing; of which:

Fig. 1 is a longitudinal vertical section of a chain

made and equipped in accordance with the principles of the present invention;

Fig. 2 is a transverse sectional elevation taken on the line 2—2, Fig. 1; and

Fig. 3 is a longitudinal section of one of the links of Fig. 1, showing the attachment-receiving surface of the link provided with an attachment thereon which differs in the spacing of the pole sockets from the attachments shown on the links in Fig. 1.

The chain shown in Fig. 1 is of a type adapted to operate solely in a horizontal plane. The chain is composed of a plurality of links 1, 1 which are pivotally connected one to the other by pintles 2, 2. The axes of the pintles 2, in this type of chain, are vertically disposed, each pintle passing through a vertically spaced pair of lugs 3, 3 formed on one end of one link and through a single lug 4 formed on the opposite end of an interconnected link, the lug 4 being disposed intermediate the vertically spaced lugs 3, 3 of the first of the interconnected links.

In the present instance, each of the links 1 is of a hollow construction and comprises a pair of substantially parallel side walls 5 and 5a, transverse end walls 6, 6, and a top wall 7, collectively providing a cavity 8 for a chain-supporting wheel 9 which is adapted to run on a suitable supporting surface 10. The supporting wheel 9 in each instance is rotatably mounted on an axle 11 which is supported in bearings 12 and 13 formed on the lower portions of the inner and outer side walls 5 and 5a respectively. The bearing 13 on the outer side wall 5a is provided with an axial extension 14 through which the axle 11 extends a cotter pin or other device 15 for securing the axle in fixed position in the link.

The top wall 7 of the link provides the above noted flat surface 20 on each of the links 1. The surfaces 20, 20 of the interconnected links of the assembled chain are disposed in a common substantially horizontal plane as illustrated in Fig. 1, and provide a substantially continuous surface for supporting the poles.

Formed in a manner to rest on the surface 20 of each link, and to be rigidly secured to the link, is a pole socket attachment 25. Each of said attachments 25 is composed of a strip 26 of suitable, and preferably a non-corrodible, metal which is bent or otherwise formed into a series of undulations to provide a plurality of individual pole sockets 27 for receiving the poles x, x in definite predetermined laterally spaced relation to each other.

In cases where the poles are adapted to sup-

port skeins of yarns, for example, it is desirable that the pole sockets be as smooth as possible in order to prevent marring of the poles, at and adjacent their opposite ends where they rest on the 5 links of the laterally spaced carrying chains composed of the links 1, the metallic strips 26 are preferably covered with a relatively soft resilient material, such, for example, as a knitted or woven tube 29 slipped over and encasing the undulated 10 strip 26.

Each socket attachment 25 is secured to a link 1 in superposed relation to the flat platform surface 20 of the link, in the present instance, by means of screws 28, 28 which pass through the 15 strip 26 and through the resilient enveloping covering 29 thereof. The screws 28 are threaded into tapped openings 30 provided in each link 1 adjacent the opposite ends thereof respectively.

As a comparative example of the spacing of 20 the sockets of the attachments of the different series, Fig. 1 shows an attachment wherein the sockets 27 are spaced apart at a distance of $1\frac{1}{2}$ " which provides for a spacing of the poles x , x in any desired multiple of $1\frac{1}{2}$, for example, spacing 25 at $1\frac{1}{2}$, 3, $4\frac{1}{2}$, 6", etc., each attachment being provided with four sockets. In the attachment shown in Fig. 3, the spacing of the sockets is 2" apart, thereby providing for a spacing of the poles in any multiple of two. Obviously, the spacing 30 of the sockets of the attachments of other series, interchangeable with the series shown in Fig. 1 or that shown in Fig. 3, may be varied to whatever extent that may be desired or required to meet a prevailing condition or circumstance necessitating a special spacing of the poles.

The point of the invention is that in all instances the pitch of the links 1, that is, the distance between the pintles 2, 2, remains constant while the pitch of the sockets of the different 40 attachments providing the desired spacing may vary to any desired extent; and each series of attachments may be readily attached to the standard links 1 without requiring any modification thereof.

45 In order to prevent axial shifting of the poles x relative to the carrying chains at the opposite sides of the conveyer the outer side of each of the carrying chains is provided with a vertical flange 24, which, in the present instance, and as shown 50 in Fig. 2, is disposed substantially in the plane of the outer wall 5a of the link 1.

While the invention has been described in connection with a chain operating in a horizontal plane, that is, wherein both the pole-carrying run 55 of the chain and the return run of the chain are disposed solely in a common horizontal plane, making the chain particularly adaptable for use in that form of apparatus disclosed in the co-pending application of Alpheus O. Hurxthal, Serial No. 713,217, filed February 27, 1934, the invention is equally adaptable to that form of pole-carrying chain disclosed in the prior patent to E. B. Ayres No. 1,584,593, dated May 11, 1926, wherein both runs of the pole-carrying chain operate in a common vertically disposed plane, and wherein the supporting wheels for the chain are rotatably mounted about the axes of the pintles by which the links of the chain are operatively connected together, the axes of the pintles in 65 such instance being disposed horizontally in place of vertically as disclosed in the present application.

I claim:

1. A pole-carrying element having a substantially continuous attachment-supporting surface

in a single plane provided at predetermined intervals with attachment-securing means, and interchangeable series of pole-spacing attachments having relatively different pole spacings and respectively provided with means adapted to cooperate with said securing means for rigidly mounting said attachments on said surface. 5

2. A pole-carrying chain comprising a multiplicity of pivotally connected links collectively providing a substantially continuous attachment-supporting surface in a single plane and equipped at predetermined intervals with attachment-securing means, and interchangeable series of pole-spacing attachments having relatively different pole spacings and respectively provided with means adapted to cooperate with said securing means for rigidly mounting said spacing attachments on said surface. 10

3. A pole-carrying chain comprising a multiplicity of pivotally connected links respectively provided with attachment-supporting surfaces, attachment-securing means on each link, and interchangeable series of pole-spacing attachments having relatively different pole spacings respectively, each attachment of each series 15 thereof being provided with means adapted to cooperate with said securing means for rigidly mounting said spacing attachments on said link surfaces respectively. 20

4. A pole-carrying chain comprising a multiplicity of pivotally connected links each provided with a substantially flat attachment-supporting surface extending substantially from end to end thereof, interchangeable pole-spacing attachments of relatively different pole spacings adapted 35 to be respectively mounted on said link surfaces and to contact therewith at varying points longitudinally thereof as determined by the pole spacings of the respective attachments, and means for securing each attachment rigidly to 40 said surface.

5. A pole-carrying chain comprising a multiplicity of pivotally connected links each provided with a substantially flat attachment-supporting surface extending substantially from end to end 45 thereof, interchangeable pole-spacing attachments of relatively different pole spacings adapted to be respectively mounted on said link surfaces and to contact therewith at varying points longitudinally thereof as determined by the pole 50 spacings of the respective attachments and each consisting of an element having a predetermined number of individual pole sockets formed therein.

6. A pole-carrying chain comprising a multiplicity of pivotally connected links each provided with a substantially flat attachment-supporting surface extending substantially from end to end thereof, interchangeable pole-spacing attachments, of relatively different pole spacings adapted 55 to be respectively mounted on said link surfaces and to contact therewith at varying points longitudinally thereof as determined by the pole spacings of the respective attachments and each consisting of an element having a predetermined plural number of individual uniformly spaced 60 pole sockets formed therein and corresponding in number to the pole spacings of the respective attachments.

7. A pole-carrying chain comprising a multiplicity of pivotally connected links each provided with a substantially flat attachment-supporting surface extending substantially from end to end thereof, interchangeable pole-spacing attachments of relatively different pole spacings adapted 70 to be respectively mounted on said link surfaces 75

- and to contact therewith at varying points longitudinally thereof as determined by the pole spacings of the respective attachments, each consisting of an undulated strip providing a predetermined number of individual pole sockets therein and corresponding in number to the pole spacings of the respective attachments, and means for securing each attachment rigidly to said surface.
8. A pole-carrying chain comprising a multiplicity of pivotally connected links each provided with a substantially flat attachment-supporting surface extending substantially from end to end thereof, interchangeable pole-spacing attachments of relatively different pole spacings adapted to be respectively mounted on said link surfaces and to contact therewith at varying points longitudinally thereof as determined by the pole spacings of the respective attachments, each consisting of an undulated strip providing a predetermined plural number of individual uniformly spaced pole sockets therein and corresponding in number to the pole spacings of the respective attachments, and means for securing each attachment rigidly to said surface.
9. A pole-carrying chain comprising a multiplicity of pivotally connected links each provided with a substantially flat attachment-supporting surface extending substantially from end to end thereof, interchangeable pole-spacing attachments of relatively different pole spacings adapted to be respectively mounted on said link surfaces and to contact therewith at varying points longitudinally thereof as determined by the pole spacings of the respective attachments, each consisting of an undulated strip providing a predetermined plural number of individual uniformly spaced pole sockets therein and corresponding in number to the pole spacings of the respective attachments, and means for securing each attachment rigidly to said surface consisting of a pair of screws respectively threaded into tapped openings formed in each link surface in a same predetermined uniformly spaced relation to each other on each link and passing through a correspondingly spaced pair of openings formed in each of the interchangeable socket-forming strips.
10. A pole-carrying chain comprising a multiplicity of pivotally connected links each consisting of a body portion provided with a substantially flat attachment-supporting surface extending substantially from end to end thereof, pivot lugs projecting in opposite directions from the opposite ends of said body portion substantially parallel to said surface, pintles extending through said lugs perpendicular to said surface, interchangeable pole-spacing attachments of relatively different pole spacings adapted to be respectively mounted on said link surfaces and to contact therewith at varying points longitudinally thereof as determined by the pole spacings of the respective attachments, and means for securing each attachment rigidly to said surface.
11. A pole-carrying chain comprising a multiplicity of pivotally connected links each consisting of a hollow body portion provided with a substantially flat attachment-supporting surface extending substantially from end to end thereof, pivot lugs projecting in opposite directions from the opposite ends of said body portion substantially parallel to said surface, pintles extending through said lugs perpendicular to said surface, a supporting wheel rotatably mounted in said hollow body portion about an axis extending at right angles to said pintles, interchangeable pole-spacing attachments of relatively different pole spacings adapted to be respectively mounted on said link surfaces and to contact therewith at varying points longitudinally thereof as determined by the pole spacings of the respective attachments, and means for securing each attachment rigidly to said surface.
12. A pole-carrying chain comprising a multiplicity of pivotally connected links each consisting of a hollow body portion provided with a substantially flat attachment-supporting surface extending substantially from end to end thereof, pivot lugs projecting in opposite directions from the opposite ends of said body portion substantially parallel to said surface, pintles extending through said lugs perpendicular to said surface, a supporting wheel rotatably mounted in said hollow body portion about an axis extending at right angles to said pintles, interchangeable pole-spacing attachments of relatively different pole spacings adapted to be respectively mounted on said link surfaces and to contact therewith at varying points longitudinally thereof as determined by the pole spacings of the respective attachments, each consisting of an undulated strip providing a predetermined plural number of individual uniformly spaced pole sockets therein, means for securing each attachment rigidly to said surface, and a flange extending at right angles to said surface adjacent one side of the socket strip to limit movement of the poles transversely of said strip.
13. A pole-carrying chain comprising a multiplicity of pivotally connected links each provided with a substantially flat attachment-supporting surface extending substantially from end to end thereof, interchangeable pole-spacing attachments of relatively different pole spacings adapted to be respectively mounted on said link surfaces and to contact therewith at varying points longitudinally thereof as determined by the pole spacings of the respective attachments, each consisting of an undulated strip providing a predetermined plural number of individual uniformly spaced pole sockets therein, means for securing each attachment rigidly to said surface, and a flange extending at right angles to said surface adjacent one side of the socket strip to limit movement of the poles transversely of said strip.

WARREN A. DICKINSON.
